(57) CLAIM

The ornamental design for a lap top case, as shown and described.

DESCRIPTION

FIG. 1 is a top view of the lap top case;

FIG. 2 is a bottom view of the lap top case;

FIG. 3 is a first side view of the lap top case;

FIG. 4 is a second side view of the lap top case;

FIG. 5 is a front side view of the lap top case;

FIG. 6 is a back side view of the lap top case;

FIG. 7 is a perspective view of the lap top case; and,

FIG. 8 is a perspective view of the lap top case in an open position.

The broken lines are shown in the views for illustrative purposes only and form no part of the claimed design.
